UNITED STATES PATENT OFFICE.

GEORGE S. HILL, OF BERWICK, PENNSYLVANIA.

HYDRAULIC PINION PULLER.

Application filed April 4, 1924, Serial No. 704,224. Renewed February 27, 1926.

To all whom it may concern:

Be it known that I, GEORGE S. HILL, a citizen of the United States, residing at Berwick, in the county of Columbia and State of Pennsylvania, have invented new and useful Improvements in Hydraulic Pinion Pullers, of which the following is a specification.

This invention relates to gear pullers, and 10 an object of the invention is to provide a gear puller in which a maximum gear or pinion pulling string may be applied to the gear or pinion to be removed from the shaft, upon the exertion of a relatively small 15 amount of operating force.

A further object of the invention is to provide a gear puller as specified, in which hydraulic power or pressure is used in conjunction with the adjustment of a feed screw 20 for removing or pulling a gear or pinion from a shaft, the said hydraulic power co-operating with the feed screw in such manner as to relieve the threads of the screw of the resisting power of the gear or pinion 25 thereby materially increasing the longevity of the feed screw and permitting the use of a relatively small light feed screw in proportion to the amount of work performed.

Other objects of the invention will appear 30 in the following detail description, and in the accompanying drawings wherein:—

Figure 1—is a side elevation of the improved gear puller showing it in use.

Figure 2—is a longitudinal section 35 through the gear pulier.

Figure 3—is a detail cross section taken on the line 3—3 of Figure 1.

Referring more particularly to the drawings, the improved gear puller comprises a 40 main cylinder 1 which has a cap 2 threaded on one end thereof. A gasket 3 is interposed between the end of the cylinder 1 and the head 2 to provide a fluid-tight connection therebetween. The cap 2 is adapted to form 45 an abutment against the end of a shaft from which a gear or pinion, as shown at 4, is to be pulled, or removed. A second cylinder 5 is slidably mounted within the cylinder 1 and it has a sleeve 6 formed axially on its 50 inner partially closed end 7, upon which sleeve a washer or gasket 8 is mounted and held tightly in place by means of a nut 9. The bore 10 of the sleeve 6 is adapted to permit oil to flow from the chamber 12 55 within the cylinder 5 into the chamber 11 within the cylinder 1 in front of the cylin-

der 5 when the cylinder 5 is forced inwardly into the cylinder 1. The piston 13 is mounted upon a feed screw 14 and it has a suitable washer 15 thereon similar to the washer 8 60 so as to provide a fluid-tight engagement with the inner wall of the cylinder 5.

The feed screw 14 threads through a closure nut 16 which is in turn threaded on the outer end of the cylinder 5. A wrench head 65 17 may be provided on the end of the feed screw 14 to facilitate manual rotation thereof.

The outer surface of the cylinder 5 is screw-threaded for a portion of its length, 70 and an arm carrying nut 18 is adjustable over the screw threaded portion. A plurality of arms 19 are pivotally connected, as shown at 20, to the nut 18 and they have gear engaging fingers 21 pivotally connected 75 thereto at their outer ends. The gear engaging fingers 21 have their inner edges 22 shaped to fit between the teeth of a gear or pinion, and their outer terminals are turned, as shown at 23 to engage against the 80 side of the gear or pinion 4, so that when the cap 2 is in abutting engagement with the end of a shaft, as at A upon which the gear or pinion 4 is mounted, and the feed screw 14 is rotated, the action caused thereby, will 85 pull the gear or pinion towards the head 2 and the gear pulling device for removing it from the shaft. During the rotation of the feed screw 14 to advance piston 13, the threads of the feed screw are relieved of much 90 of the wear and the resisting pressure by the action of the oil in the chambers 11 and 12. The pressure of the piston 13 against the oil 95 causes cushioning action, resulting in the oil bearing the majority of the working strain of the device.

It is, of course, to be understood, that the invention may be constructed in various other manners and the parts associated in different relations, and therefore, I do not 100 desire to be limited in any manner, except as set forth in the claims hereunto appended.

What I claim is:

1. A gear remover comprising a cylinder 105 adapted to contain a fluid, a second cylinder slidable within said first cylinder and having fluid-tight connection therewith, a reduced duct establishing communication between the interiors of said first and second cylinders, a piston in the second cylinder, a nut 110 threaded on said second cylinder, a feed screw connected to said piston and threaded

through said nut, and means carried by said second cylinder for engagement with a gear.

2. A gear remover comprising a cylinder adapted to contain a fluid, a second cylinder 5 slidable within said first cylinder and having fluid-tight connection therewith, a reduced duct establishing communication between the interiors of said first and second cylinders, a piston in the second cylinder, a nut threaded on said second cylinder, a feed screw connected to said piston and threaded through said nut, a nut adjustable on said second cylinder, and gear engaging arms pivotally carried by said last named nut.
- 15 3. A gear remover comprising a cylinder adapted to contain a fluid, a second cylinder slidable within said first cylinder and having fluid-tight connection therewith, a reduced duct establishing communication between the 20 interiors of said first and second cylinders, a piston in the second cylinder, means for feeding said piston longitudinally in the second cylinder, means for engagement with

a gear to remove the gear from a shaft upon forcing inward feeding of the piston within 25 the second cylinder, and a shaft abutting cap removably mounted on one end of said first named cylinder.

4. A gear remover comprising a cylinder adapted to contain a fluid, a second cylinder 30 slidable within said first cylinder and having fluid-tight connection therewith, a reduced duct establishing communication between the interiors of said first and second cylinders, a piston in the second cylinder, a nut threaded on said second cylinder, a feed screw connected to said piston and threaded through said nut, a nut adjustable on said second cylinder, gear engaging arms pivotally carried by said last named nut, and a shaft abutting 35 cap removably mounted on one end of said first named cylinder.

In testimony whereof I affix my signature.

GEORGE S. HILL.
